(57) **CLAIM**

The ornamental design for a bicycle bottom bracket tool, as shown and described.

DESCRIPTION

FIG. 1 is a front perspective view of a bicycle bottom bracket tool.

FIG. 2 is a rear perspective view of the bicycle bottom bracket tool and illustrating one configuration of the teeth around the rearward interior periphery of the tool.

FIG. 3 is a left side elevation view of the bicycle bottom bracket tool.

FIG. 4 is a right side elevation view of the bicycle bottom bracket tool.

FIG. 5 is a top view of the bicycle bottom bracket tool.

FIG. 6 is a bottom view of the bicycle bottom bracket tool.

FIG. 7 is a front elevation view of the bicycle bottom bracket tool.

FIG. 8 is a rear elevation view of the bicycle bottom bracket tool.

FIG. 9 is a rear elevation view of the bicycle bottom bracket tool showing an alternative configuration of the teeth around the rearward interior periphery of the tool; except for the alternative configuration of the teeth around the rearward interior periphery of the tool, all other features of the tool are the same as shown in FIGS. 1-7; and,

FIG. 10 is a rear elevation view of the bicycle bottom bracket tool showing another alternative configuration of the teeth around the rearward interior periphery of the tool; except for the alternative configuration of the teeth around the rearward interior periphery of the tool, all other features of the tool are the same as shown in FIGS. 1-7.

The broken lines in the drawings illustrate portions of the bicycle bottom bracket tool that form no part of the claimed design.
